BUILDER MECHANISM FOR SPINNING FRAMES

Sigurd H. Helland, Whitinsville, Mass., assignor to Whitin Machine Works, Whitinsville, Mass., a corporation of Massachusetts

Application May 19, 1938, Serial No. 208,869

5 Claims. (Cl. 242—43.3)

This invention relates to machines for spinning yarn, and relates more particularly to the mechanism which controls the winding or building of the bobbins in such a machine. Builder mechanism for this purpose is shown and described in the prior patent to Kooistra, No. 1,926,390, issued September 12, 1933. The mechanism disclosed in said patent is operative not only to wind the bobbins but also to automatically restore the parts to initial position after a predetermined winding period.

It is the general object of my present invention to improve the operation of the Kooistra builder mechanism by the provision of improved means for accurately timing the end of the wind and the restoration of the builder mechanism to initial condition.

More particularly, I provide means for effecting such restoration when the builder lever is in a predetermined position only. In the preferred form, the restoration takes place when the builder lever is at the highest point in its path of movement.

My invention further relates to arrangements and combinations of parts which will be herein-after described and more particularly pointed out in the appended claims.

A preferred form of the invention is shown in the drawings, in which

Fig. 1 is a side elevation of my improved builder mechanism, with parts of an associated spinning frame shown in section;

Fig. 2 is a plan view of the builder mechanism, looking in the direction of the arrow 2 in Fig. 1;

Figs. 3 and 4 are sectional end elevations, taken along the lines 3—3 and 4—4 respectively in Fig. 1;

Fig. 5 is a sectional side elevation, taken along the line 5—5 in Fig. 4;

Fig. 6 is a detail end elevation, looking in the direction of the arrow 6 in Fig. 2; and

Fig. 7 is a partial side elevation similar to Fig. 1 but showing certain parts in a different position.

Referring to the drawings, I have shown portions of a spinning frame including an end frame 10, a ring rail 11 (Fig. 1) fixed to the end frame 10 and supporting a plurality of spinning rings R, and a spindle rail 12 supporting a plurality of spindles S.

Each spindle rail 12 is mounted to slide vertically on upright guide rods 14 fixed to a bottom rail 15. The spindle rails 12 on the two opposite sides of the machine are connected by cross members 16 (Fig. 1), having hooks 17 to

which flexible bands 18 are connected. The upper ends of the bands 18 extend partially around the peripheries of grooved pulleys 20 and are secured thereto.

The pulleys 20 are mounted on shafts 22 on opposite sides of the machine and extending lengthwise thereof. These shafts 22 are provided with sprockets connected by a cross chain 25 (Fig. 1). The chain 25 is so connected to its sprockets that when one shaft 22 is rotated in one direction, the opposite shaft 22 will be correspondingly rotated in the opposite direction.

The shaft 22 at the right-hand side of the machine is also provided with a sprocket 26 (Fig. 1) to which is secured a chain 27 which extends downward and is secured at its lower end to a sprocket 28 mounted on a short shaft 29 having bearings in an upwardly projecting portion of a builder lever 30.

The lever 30 is provided with a forked hub 31 (Fig. 2) at its rear end, loosely mounted on a drive shaft 32 rotatable in a bearing 33 on the end frame 10. At its free end, the builder lever 30 is provided with a roll 35 (Fig. 1) engaged by a heart-shaped builder cam 36 mounted on a drive shaft 37 rotatable in a bearing 38 (Fig. 2) on the end frame 10. As the cam 38 is rotated, the builder lever 30 will be periodically forced downward, tensioning the chains 27 and 25 and the flexible bands 18 and thus raising the spindle rails 12 and spindles S relative to the fixed ring rails 11 and rings R. The weight of the spindle rails 12 and associated parts is more than sufficient to counterbalance the weight of the builder lever 30 and to hold the roll 35 firmly against the cam 36.

For the purpose of rotating the sprocket 28 on the lever 30 alternately in opposite directions and at different speeds, I provide three short shafts 40, 41 and 42 (Fig. 1) mounted in bearings in the lever 30 and in axial alignment with each other. The shaft 40 is provided at one end with a bevel gear 44 engaged by a bevel gear 45 (Fig. 2) on the end of the drive shaft 32 previously described. At its opposite end, the shaft 40 is provided with a toothed clutch member 46 (Fig. 1) positioned for engagement by a similar toothed clutch member 47 keyed to and slideable on the inner end of the intermediate shaft 41.

A worm 50 (Fig. 1) is fixed to the middle portion of the shaft 41 and engages a worm gear 51 (Fig. 2) on the short shaft 29 on which the sprocket 28 is mounted. The outermost shaft 42 (Fig. 1) in the builder lever 30 is provided

20

50

55

with a toothed clutch member 55 at its inner end, positioned for engagement by a similar clutch member 56 keyed to and slideable on an outer end portion of the intermediate shaft 41.

5 The clutch members 47 and 56 are grooved to receive yoke arms 58 and 59 (Fig. 1) mounted on a shaft 60 slideable in bearings 61 projected downward from the builder lever 30. The parts are so proportioned that when one driving clutch member 47 or 56 is engaged, the other driving clutch member is inoperative.

A reversing lever 62 (Fig. 7) is pivoted at 63 on the builder lever 30 and has a downwardly extending end portion 64 provided with a stud 65 positioned between spaced flanges 66 and 67 on a collar 68 fixed to the sliding shaft 60. The lever 62 thus has a lost motion connection with the sliding shaft 60.

20 The lever 62 also has a cam-shaped projection 70 (Fig. 7) engaged by a spring plunger 71 mounted in a casing 72 secured to the side of the builder lever 30. The plunger 71 holds the lever 62 yieldingly in either of its operative positions until positively moved therefrom and also 25 accelerates the latter part of the reversing movement of the lever.

20 The lever 62 is positioned for engagement by lugs 74 and 75 (Fig. 7) adjustably secured to a disc 76 (Fig. 3) fixed to the outer end of the shaft 29 on which the worm wheel 51 and sprocket 28 are mounted.

35 The outer shaft 42 (Fig. 1) on the builder lever 30 is provided with a ratchet wheel 80 (Fig. 6) at its outer end, engaged by a pawl 81 pivoted at 82 to the outer end of an arm 83, which arm in turn is pivoted to swing about the axis of the shaft 42. The limit of downward or inoperative movement of the pawl 81 and arm 83 is determined by engagement of the arm 83 40 with an adjustable stop screw 84.

40 A rod 86 is pivoted to the arm 83 and is provided with spaced collars 88 and 89 positioned for engagement by a lifter arm 90 (Fig. 1), pivoted on a stud 91 which also rotatably supports the cam roll 35 previously described. A 45 second arm 93 projects upward from the stud 91 and is preferably formed integral with the lifter arm 90.

50 The ram 93 is positioned for engagement by a stud 95 (Fig. 1) on the side of the cam 36 and is rocked to raise the arm 90 at each rotation of the cam. Such upward movement of the arm 90 causes the arm to engage the upper spaced collar 88 and to positively lift the arm 83 and pawl 81, thus advancing the ratchet wheel 80, a predetermined number of teeth. The amount of feed is regulated by the position of the stop screw 84.

55 When released by the stud 95, the weight of the arm 90 causes the arm to swing downward, engaging the lower collar 89 and giving the feed pawl 81 and arm 83 a return movement to inoperative position.

60 The parts thus far described are as shown in 65 the Kooistra patent and in themselves form no part of my present invention, which relates more particularly to certain features which will now be described.

65 In the Kooistra builder mechanism, the sliding shaft 60 (Fig. 1) was shifted to reverse the clutch engagement when the lug 74 had moved the lever 62 far enough beyond the point of the spring plunger 71 so that the rocking movement of the lever 62 was abruptly completed. The time of 70 movement, however, was subject to considerable

variation, and was not definitely related to the angular position of the cam 36.

It is desirable to reverse the builder mechanism when the builder lever 30 is at its highest point and with the cam roll 35 in the heel of the cam 36. At this point, the clutch members 55 and 56 are not under pressure and can be easily disengaged. Also, the wind-back operation, which takes about one-half a revolution of the cam, will be completed with the cam roll 35 on the point of the cam and with the spindle rails 10. in their highest positions.

In order to achieve this result, I provide a latch pin 100 (Fig. 4) slideable in a vertical bearing 101 on the builder lever 30 and having its lower end projecting into the annular groove 102 in the right-hand clutch collar 56 which is engaged by the yoke arm 59. One side of the pin 100 is preferably slabbed off as indicated at 103, so that the end of the pin is somewhat narrower 20 than the width of the groove 102.

15 A lock arm 110 is pivoted at 111 (Fig. 4) on the builder lever 30 and has a circular head 112 seated in a recess in the side of the pin 100. A spring plunger 113 holds the rock arm 110 and 25 pin 100 normally in the position shown in Fig. 4.

An extension 115 of the rock arm 110 is positioned for engagement by a stop screw 116 when the builder lever reaches its highest position, with the cam roll 35 in the heel of the cam 36. 30 The screw 116 is adjustable in a fixed bracket 117.

The operation of my improvements in determining the exact time of reversal of the winding mechanism on the builder lever is as follows:

Assuming that the lug 74 has moved the lever 62 to the position shown in Fig. 7, the spring plunger 71 will attempt to complete the shifting movement of the lever 62 but such completion will be prevented by the pin 100, which will allow the sliding shaft 60 to move far enough 40 to disengage the clutch teeth of the members 55 and 56 but not far enough to engage the clutch members 46 and 47.

The sliding shaft 60 will remain in this neutral position until the builder lever 30 reaches its 45 highest point of travel, with the roll 35 in the heel of the cam 36. In this position the portion 115 of the rock arm 110 is engaged by the stop screw 116 and is rocked to raise the pin 100 out of the annular groove 102. The sliding shaft 60 is thus released and completion of the shifting movement of the lever 62 takes place.

The usual mechanism, not shown, is provided for stopping the machine when the wind-back operation is completed.

55 By the addition of my attachment to the Kooistra builder lever, the uncertain timing of the Kooistra mechanism is remedied, with the beneficial results previously set forth. It will also be noted that my improvements comprise 60 only two relatively simple moving parts, and that simple and convenient means for adjustment of the device is provided.

Having thus described my invention and the advantages thereof, I do not wish to be limited 65 to the details herein disclosed, otherwise than as set forth in the claims, but what I claim is:

1. In a spinning frame having a rail, a builder cam, a builder lever, a rail-shifting shaft rotatably mounted on said lever, means for intermittently rotating said shaft in one direction during the winding of the bobbins, means for continuously rotating the shaft in the reverse direction during the wind-back of the rail, alternately operative clutch member shiftable to establish 70

driving connections between said shaft and said two rotating means selectively, a clutch-shifting device, and automatic means to actuate said device, that improvement in builder mechanism which consists in providing means to hold said clutch members in neutral position until said cam and builder lever occupy a predetermined relation, and means to release said clutch members for further movement to effect the wind-back when said predetermined relation is established.

2. In a spinning frame having a rail, a builder cam, a builder lever, a rail-shifting shaft rotatably mounted on said lever, means for intermittently rotating said shaft in one direction during the winding of the bobbins, means for continuously rotating the shaft in the reverse direction during the wind-back of the rail, alternately operative clutch members shiftable to establish driving connections between said shaft and said two rotating means selectively, a clutch-shifting device, and automatic means to actuate said device, that improvement in builder mechanism which consists in providing a stop permitting disengaging movement only of said clutch members by said automatic means, and a device to withdraw said stop in a predetermined position of said builder lever and thereby permit completion of the shifting of said clutch members by said automatic means.

3. In a spinning frame having a rail, a builder cam, a builder lever, a rail-shifting shaft rotatably mounted on said lever, means for intermittently rotating said shaft in one direction during the winding of the bobbins, means for continuously rotating the shaft in the reverse direction during the wind-back of the rail, alternately operative clutch members shiftable to establish driving connections between said shaft

and said two rotating means selectively, a clutch-shifting device, and automatic means to actuate said device, that improvement in builder mechanism which consists in providing a stop having a lost motion connection with said clutch-shifting device and operative to prevent shifting movement of said device beyond neutral position, and means to withdraw said stop when said builder lever reaches a predetermined position.

4. The combination in a builder mechanism as set forth in claim 3, in which said latter means comprises a rock arm mounted on said builder lever and connected to said stop, and a fixed abutment engageable by said rock arm as said builder lever approaches its upper limit of travel, whereby said rock arm is moved to withdraw said stop.

5. In a spinning frame having a rail, a builder cam, a builder lever, a rail-shifting shaft rotatably mounted on said lever, means for intermittently rotating said shaft in one direction during the winding of the bobbins, means for continuously rotating the shaft in the reverse direction during the wind-back of the rail, alternately operative clutch members shiftable to establish driving connections between said shaft and said two rotating means selectively, a clutch-shifting device, and automatic means to actuate said device, that improvement in builder mechanism which consists in providing a device normally operative to prevent initial clutch-shifting movement by said automatic means beyond neutral position, and means operative at a predetermined point in the cycle of movement of the builder lever to render said normally operative device inoperative and thereby enable said automatic means to complete the clutch-shifting movement.

SIGURD H. HELLAND.
